UNITED STATES PATENT OFFICE.

SOLOMON D. WARFIELD, OF BALTIMORE, MARYLAND.

GREEN-CORN CUTTER.

SPECIFICATION forming part of Letters Patent No. 258,174, dated May 16, 1882.

Application filed September 24, 1881. (Model.)

To all whom it may concern:

Be it known that I, SOLOMON D. WARFIELD, of the city of Baltimore and State of Maryland, have invented certain Improvements in 5 Green-Corn Cutters, of which the following is a specification.

This invention relates to certain improvements in a green-corn cutter for which Letters Patent of the United States No. 247,718 were 10 granted to me on the 27th day of September, 1881. The invention, as described in the said Letters Patent, briefly stated, consists in a machine in which an ear of corn supported axially between centers is stripped of the adhering 15 grain by means of a longitudinally-moving knife in a series of cuts, the ear being partially revolved after each operative movement of the knife, which has attachments whereby a uniform depth of cut is effected without reference 20 to irregularities in the shape of the ear. In the said invention no devices are used to assist the operator in centering the ear, the accurate placing of the same centrally on the points prepared for its reception being one in which the 25 dexterity of the operator is brought into play.

One object of my present invention is, therefore, to furnish the machine with such contrivances as will admit of unskilled labor being used, and render the centering of the ear an operation requiring little or no dexterity or care 30 on the part of the operator.

To this end my invention consists, first, in combining with the centering points or devices for holding and revolving the ear contrivances 35 into which the ends of the ear are placed, and which automatically guide the ear to the centering points; and, further, to the construction of these guiding contrivances, whereby they are automatically moved out of the way or track of 40 the knife and its attachments after the centering operation and returned to their original positions after the grain has been stripped from the cob, ready to receive another ear.

The invention consists, secondly, in combining 45 with the longitudinally-moving knife and its connections a scraper, preferably adjustable in position, which follows the knife in its cutting stroke and removes from the cob any portion of the grain left adhering thereto.

50 The said invention consists, thirdly, in a chute to receive the grain and cobs after the

cutting operation and to guide them in different directions, and in combining with the knife a deflecting device to give the severed grain, as it leaves the cob, a movement in a common 55 direction, and thereby prevent scattering.

In the further description of my said invention which follows, reference is made to the accompanying drawings, forming a part there- 60

Figure I is a perspective view of the im- 65 proved machine. Fig. II is a similar view of a part of the machine not shown in Fig. I, and on an enlarged scale. Figs. III, IV, V, VI, VII, VIII, IX, and X are geometrical views of parts of the machine on an enlarged scale.

Similar letters of reference indicate similar parts in all the views.

A is the bed-plate of the machine, supported 70 on legs a.

B is a revoluble shaft sustained in a frame, C, and having a pointed blade or driving-center, b, at its inner end, which is inserted in one end of the ear of corn from which the grain is to be stripped. The other end of the ear of 75 corn is supported by a bar, D, having a stationary center, e. The bar D is adapted to slide longitudinally in a stand, d, toward and from the driving-center, and it is influenced to a retracted position by means of a weighted 80 chain, e, which extends from its outer end over a pulley, as shown in Fig. I. Although a weighted chain, as described, is preferred as means for retracting the bar D, a spring may be employed without materially changing the 85 character of the invention. A second chain, f, leads from the bar D over a pulley or sheave to a treadle, g, by means of which the said bar can be forced toward the driving-center in the 90 operation of centering the ear, hereinafter de- 95 scribed. Through the agency of these devices the operator may use his foot to perform the centering operation, instead of his hand, as in the patented invention.

E are centering prongs extending from a 95 collar, h, adapted for movement longitudinally of the shaft B. These prongs project radially from the collar h, and their expansion is such that the largest ear may be easily placed within them. A pin, i, on the collar h, passes 100 through a slotted weighted lever, F, pivoted to the bed-plate or some other fixed part of the

machine, the object of which will hereinafter appear. The prongs have two main or fixed positions—viz., one with their flared ends projecting over the driving-center, as shown in Fig. V, and with the said ends thrown back, as shown in Fig. VIII. The first-named position is the one which the prongs occupy at the commencement of the centering operation, and the second that when the centering is accomplished and the cutting action is about to take place. G G are centering-prongs similar in construction to the ones E E, projecting from a collar, k, placed loosely on the bar D, which has a pin, l, which enters a slot in the weighted lever H. This second lever is pivoted to a downward extension, m, of the bar D. Consequently its relative position with reference to the said bar is not changed by the lateral movement of that device.

I is a knife secured rigidly to a carrier, K, pivoted to a holder, L, supported by and adapted to slide on guide-rods n, and a reciprocating motion of the knife and its attachments is effected through the medium of a crank, M, and connecting-rod o. A roller, N, is adjustably attached to the knife-carrier K and rests on the ear in advance of the knife to give a uniform depth of cut without reference to any longitudinal curvature or irregularity in the shape of the ear. The rear part of the knife I is turned upward, as shown in Fig. X of the drawings, so that the grain when removed from the cob may be thrown laterally off the knife, as will be readily understood.

O is a scraper hinged to an arm, P, pivoted to the holder L in like manner to the carrier K. A spring, Q, has the effect of retaining the scraper in contact with the cob in the rear of the knife, and the scraper removes any portion of grain left adhering to the cob. The hinging of the scraper to the arm P admits of that contrivance adapting itself to any peculiarity of shape in the cob. The arm P is preferably in two parts, as shown in Figs. IX and X—that is to say, with the outer section susceptible of a limited axial movement in order that the scraper may change its angle with reference to the cob in its forward and backward motions.

In Fig. X the knife-carrier and the scraper and its attachments are shown as elevated to a much higher position than they ever attain in the operation of the machine. This is done to illustrate their construction and mode of attachment to the holder in a single view.

R R are miter-gears connecting the shaft B with the counter-shaft S, on the outer end of which counter-shaft is fastened a ratchet-wheel, T. A rod, p, projecting from the knife-holder L at each backward movement of the said holder and its attachments, comes in contact with a spring-lever, q, carrying a pawl, r, which engages with the teeth of the ratchet-wheel T and effects a partial rotation of the shaft B and the ear. The ratchet-wheel and gearing with their attachments are preferably arranged

so that the ear will be stripped of its grain in four or five cuts of the knife.

U is a guide-rod, upon which the knife-carrier rides as the knife passes beyond the end of the ear in its backward movement, thus preventing its contact with the shaft B or the frame C. A similar guide-rod, V, is fastened to the bar D, and its office is substantially the same as the one U, only that it comes into contact with the knife-carrier in the forward or cutting stroke.

W is a rod having an eye, t, at one end, which encircles the driving-center, and it is confined in suitable supports on the bed-plate A, and is adapted to have a longitudinal movement. The other end of the rod W is bent upward and to such position as to come in contact with a brace on the guide-rod V as the same is forced back. A lateral extension, u, of the rod W engages with the lever F in its backward movement, and through it changes the position of the prongs E from the one shown in Fig. VIII to that illustrated in Fig. V, as will be hereinafter more particularly described. The corresponding change in position of the centering-prongs G on the bar D in the retraction of the said bar is effected by the collar k, from which the said prongs extend, coming into contact with the stand d.

The centering-prongs E and G being placed as shown in Figs. IV and V and the knife moved back to its extreme limit, the operation of the machine is as follows: The ear of corn is first inserted between the centering-prongs E, and the bar D, with its centering-prongs G, moved up to it by means of the treadle g and the mechanism connecting it to the said bar. As soon as pressure is placed upon the ear by means of the treadle the two sets of centering-prongs yield and are forced back, and the ear brought into contact with the center points which enter it. In this action the weighted levers F and H are thrown slightly past the vertical line, after which gravity causes them to move still farther in the same direction, thus carrying the centering-prongs with them and out of the way of the knife. The ear being centered, the operator, still keeping his foot on the treadle, rapidly turns the crank, causing the knife to make a series of cuts and the ear a series of partial revolutions while the knife is making the inoperative strokes. The cob being now stripped of its grain and scraped, the operator removes his foot from the treadle, when the weighted chain causes the bar D to be suddenly drawn back or retracted, which releases the cob and discharges it, and places the centering-prongs in their original position, ready for the reception of another ear. A chute, X, (shown in Fig. II,) secures the corn and cob, and the latter, falling on a system of transverse wires, w, is deflected to an aperture, x, having a hinged door, y, opening outward, through which it is discharged to any suitable receptacle. The corn is guided by the upwardly-turned rear end of the knife to the

chute, and thence to another receptacle placed underneath the machine for its reception.

In the foregoing description I have used the word "centering-points" to designate the devices for supporting the ear axially; but it is evident that any other device, even if devoid of points, that will sustain the ear in the required position during the cutting operation will answer the purpose to some extent.

10 I claim as my invention—

1. In a green-corn cutter, the revoluble shaft and the bar carrying the centers for supporting an ear of corn, provided with flaring centering devices adapted to yield and expose 15 the said ear to the said centers as the ear is compressed endwise in the centering operation, substantially as and for the purpose specified.

2. In a green-corn cutter, the centering prongs or devices for centering the ear of corn, 20 connected to weighted pivoted levers, whereby they are susceptible of longitudinal movement on their respective shafts and bars by the force of gravity in excess of that imparted to them by the endwise compression of the ear, 25 substantially as and for the purpose specified.

3. In a green-corn cutter, the longitudinally-moving knife for removing the grain from the cob, combined with a longitudinally-moving scraper adapted to bear on the cob with a yielding pressure, substantially as and for the purpose specified. 30

4. In a green-corn cutter, the longitudinally-moving knife for separating the grain from the cob, turned upward at its rear end to form a deflector for the severed grain, substantially 35 as and for the purpose specified.

5. In a green-corn cutter, a chute or pan adapted to receive the grain and cob after their separation, provided with interior deflecting devices to conduct the cob to an exit-aperture distinct from that for the grain, substantially 40 as specified.

6. In combination with the bar D, the weighted chain e, chain f, and treadle g, substantially as and for the purpose specified.

SOLOMON D. WARFIELD.
